ELECTRICAL ALTERNATING CURRENT
GENERATORHoward J. Tyzzer, Caldwell, N. J., assignor to
Ferris Laboratories, Boonton, N. J., a corpora-
tion of New Jersey

Application June 28, 1944, Serial No. 542,497

11 Claims. (Cl. 250—36)

1

My present invention broadly relates to generating electrical alternating currents, and more particularly to generating the same in a system making use of an electronic tube associated with electrical circuits adapted to make the generation thereof possible under a variety of circumstances.

A particular object of my present invention is to make certain standard electronic tubes and associated circuits more elastic in the matter of the range of frequencies throughout which electrical alternating currents can be effectively generated with a minimum of circuit adjustments being needed to arrive at the particular results.

Practice of my present invention requires a type of electronic tube that will, when properly energized, materially amplify electrical alternating currents, and a specific object in practicing the same is to effectively make allowances for the inevitable lack of uniformity of the inherent characteristics of standard electronic tubes of the same type arising in particular out of mass production, and the differences in the constructions of different types of amplifying electronic tubes particularly with respect to the respective placements of the vital internal elements thereof with which my present invention can accordingly be practiced.

In practicing my present invention, I deal in particular with the generation of electrical alternating currents of very high and ultra high frequencies as distinguished from the ordinary high frequencies common to radio operation practices until recently; and I have found that in certain regions therein, dependent somewhat upon the particular type of amplifying electronic tube used, certain critical conditions arise that require special treatments to remove them which are to be more fully dealt with later, the manners in which the respective treatments are applied being of such natures as to be specific objects of my present invention. In the cases of all of the standard amplifying electronic tubes accordingly suitable for participating in practicing my present invention, I have found that these critical conditions arise somewhere in the frequency range above 100 megacycles.

In generating electrical alternating currents of low and comparatively high with respect to low frequencies with amplifying electronic tubes and associated circuits, it has consistently been done by using one of several methods of feeding some component of the alternating manifestations of the amplified energy from the output circuit into the input circuit in such a manner that the

2

active alternating energy of the input circuit is built up to a point where the desired volume of generated electrical alternating current is reached, the different circuit components and arrangements of them in the cases of the several methods having long been common knowledge. However, I have found without exception that in cases of the several methods each becomes less and less effective in the matter of causing generation as the frequencies desired increase after the frequency of 100 megacycles is reached to soon thereafter become totally ineffective in that the generation involved is no longer had.

Considering this matter of thus ceasing to generate from a technological theory point of view, the suggested thereby reason for it is that the building up of the input energy required no longer takes place due to too much departure from coincidence in the timing involved; so that resorting to increasing the component of the alternating energy fed into the input circuit at those frequencies above 100 megacycles involved in an effort to overcome said ceasing to generate at a point beyond which it is desired to maintain progressive generation of electrical alternating currents of considerably higher frequencies apparently tends to make the actions responsible for the ceasing to generate all the more effective, to overcome which the radical departures from prior practices I have called into play are seemingly the only answers.

It is confidently anticipated that other objects of my present invention perhaps of lesser importance than those given will be readily apparent to those competently acquainted with the particular art; so having given the principal objects of the same, it will now be described with the aid of the two figures of the accompanying drawings, in which figures, to a substantial extent, like symbols have to do with substantially like in kind or in function elements.

Fig. 1 schematically displays my present invention in its more or less generic form.

Fig. 2 schematically displays supplements to Fig. 1 whereby the range of its application is materially extended.

Referring to Fig. 1, element T indicates an envelope of an electronic tube having a source of electrons in the cathode K indicated as heated by a filament F supplied with current by a battery B', a control grid CG, a screen grid SG made positive by being connected to battery B through a voltage reducing resistance R', an outer grid OG maintained at cathode potential by being connected thereto internally of en-

velope T and an anode A maintained at a positive potential by being connected to the positive potential side of battery B. As is well known, the tube described is inherently capable of materially amplifying electrical alternating currents or impulses because of the presence of control grid CG, and that when said tube is in action said grid will become and remain negative with respective to cathode K because of the presence of the grid-leak resistance R.

Element L indicates an inductance element, which may be either in rod or coil form depending upon how small the inductance must be at the very high and ultra high frequencies to be dealt with, and which, with variable capacitance CT and fixed capacitance C1'', constitute the principal means by which the frequencies of the possible to generate electrical alternating currents are determined. However, it must be taken into consideration that all artificial and inherent inductances and capacitances in any wise in a position to participate in the inductive and capacitance reactances of the principal means sum up therewith in determining the frequencies of the possible to generate electrical alternating currents.

Element L' indicates a coupling to inductance L in a position to extract a component of electrical alternating current therefrom, a substantially mid portion point of which is grounded as indicated by G'' and is consequently maintained at the potential of cathode K through ground G; from which it is perfectly clear that when the system is actively in operation at any one instant the respective potentials of the indicated terminals a and b are opposite in polarity except at those instants when the potentials of the positive and negative half cycles of the electrical alternating currents become zero in shifting in polarity. As indicated, through switch S a choice may be made in connecting either terminal a or b to control grid CG through grid lead GL and capacitance C. In addition to these connections, switch S provides through terminal c for making the same connection of the termination of inductance L to control grid CG.

As typical examples of what I have found as taking place in the matter of frequencies at which generation of electrical alternating currents is had when the three specified different connections are made; in the case of the connection from terminal a, in moving upward from below 100 megacycles an absolute shut down occurred at 110 megacycles; in the case of the connection from terminal b, in moving downward from 140 megacycles an absolute shut down occurred at 100 megacycles; and in the case of the connection from terminal c, in moving downward from 180 megacycles, an absolute shut down occurred at 140 megacycles.

In following up the above outlined typical examples, on shortening grid lead GL as much as possible with it connected to terminal a it was found that the shut down occurred at 120 megacycles instead of 110 megacycles; and on shunting the resistance R with a capacitance C' with the grid lead GL connected to terminal c, in moving downward, that shut down occurred at 100 megacycles instead of 140 megacycles.

As was expected by me in connection with these points of shut down which, due to variations in the constructions of different types of amplifying electronic tubes and particularly in the respective placements of the vital internal elements, shift to some extents from those definitely given,

said shifting is not enough to make it unuseful to introduce regulation of the same by adjustment of the length of grid lead GL and varying the capacitance of the indicated variable capacitance device C' when found to be respectively needed in the cases of working with different types of amplifying electronic tubes. Because of capacitance C' being optionally supplementary, its presence indicates a preferred form of the arrangement of Fig. 1.

Referring to Fig. 2, it principally differs from Fig. 1 in displaying a plurality of selective means by which the frequencies of the possible to generate electrical alternating currents are determined. This inclusion becomes eminently important in cases of working in more than one band of frequencies calling for shifting from one artificial inductance to another, in which cases it could happen that the frequency at which shut down occurs would call for another artificial inductance of a different inductance value in order that operations at the different frequencies involved may be carried on. In such cases, if each artificial inductance is built to have its own coupled thereto energy extraction, such as L' in Fig. 1, means, it is gifted with the potentiality of facilitating the called for switchover.

In the elements symbolized by L1, CT' and C2', Fig. 2 schematically displays a duplication of the principal means by which the frequencies of the possible to generate electrical alternating currents are determined, and further schematically displays in element L1' that the artificial inductance L1 is equipped with its own coupled thereto energy extracting means, but there is the difference that the respective different inductance values of L and L1 go to make up a design making possible working in different bands of frequencies with reduced complications in making the change over.

As to means for expeditiously changing over from one band to another, means for maintaining the anode A at its required positive potential are schematically displayed in its connection to rotary element P having affixed thereto a conductive arm D terminated by a conductive indicated brush of any suitable material for making conductive contact with either one of the arc shaped conductors d and d' which are respectively displayed as connected to the positive side of battery B through the artificial inductances L and L1, respectively. Rotatable with element P, but not in conductive contact therewith, is a switch arm S terminated in a preferably curved conductive plate E which, on being rotated, predeterminedly takes up respective positions abreast of preferably curve like it conductive plates a, b, c, a', b' and c' to thereby successively form with each of them a capacitance effect replacing that of capacitance C of Fig. 1, and which is connected to control grid CG through grid lead GL and its connection to switch arm S. With this arrangement, the plates a, b and c respectively take the places of contacts a, b and c in Fig. 1 while at the same time eliminating the need for capacitance C of Fig. 1, and the plates a', b' and c' take over for their own band when the other band is placed out of commission by having arms D and S join in with them in taking over. Since due to the very high frequencies involved the required capacitance in the grid lead GL is very small, it is accordingly and yet helpfully necessary to use correspondingly small dimensions in designing the capacitance introducing plates E, a and a', etc.

I have found that with a capacitance device designed with sufficient mass to effectively and materially reduce the inherent ohmic resistances and inductive reactances therewith with the latter rapidly increasing the higher and higher the frequencies of the electrical alternating currents with which used become, even in the cases of the high, very high and ultra high frequencies with which I deal, a single device of the kind can be successfully used as the variable devices CT and CT' displayed in Fig. 2 with a substantial number of different in value artificial inductances L, L₁, etc., to cover an extremely wide range of such frequencies in a number of bands; and that all of the change over operations possible in the cases of Figs. 1 and 2 can be automatically carried out by operations arising out of rotatory movements of the usual shafting of variable capacitance devices. I include an indicated display of these findings in Figs. 1 and 2 by linking the capacitances schematically displayed to the controls schematically displayed by dotted lines. The points at which the automatic actions take place are easily transferable to and indicatable on the usual variable capacitance device dial.

From a strict technological theorizing point of view, I am not certain as to what factors are involved in the way of relative actions that are responsible for the phenomena behind the shiftable results I have obtained; however, it seems that to a large extent they involve time factors that are not at all susceptible to being rooted out and pinned down. However, thanks to the tell tale instruments we now have, I have been able to quite accurately find at what points the opposing factors sufficiently sum up to force an absolute shut down, which, from a practical application point of view, is all that need be actually known.

I find it particularly desirable to electrostatically screen the control grids CG schematically shown by Figs. 1 and 2 from the respective anodes of the tubes involved by the properly energized for the purpose screen grids SG also schematically shown by said figures, as it is clearly obvious that unless such is done there will be in each case a second electrostatically reactive energy feedback path between the respective anode-cathode and grid-cathode circuits shown, which, instead of offering any co-operative advantage to the functioning of my system, clearly can well serve in each case as a source of very difficult to handle complications which can well be even too difficult to handle at all in connection with stably generating electrical alternating currents having the very high and ultra high frequencies in which I am particularly interested. Furthermore, said electrostatic screening obviously tends to make the alternating currents generated more perfectly sinusoidal in wave form than would otherwise be the case.

While I have described my present invention in certain confined respects, it is apparent that modifications may be made and that no limitations are intended other than those imposed by the scope of the appended claims.

What I claim as new and desire to secure by Letters Patent of the United States is as follows:

1. In a system for generating electrical alternating currents of sinusoidal wave form in a region of ultra high frequencies somewhere in which the inherent nature of the system per se renders it without the power to further generate: the combination of a standard electronic tube having an electron source in spaced relation to an effective electron attracting positive potential

anode and a negative potential control grid interposed therebetween in normal spaced relations thereto; a positive potential screen grid interposed between said grid and said anode; a circuit having paralleled inductance and variable capacitance of such respective values as to have electrical natural periods corresponding in part at least to the ultra high frequencies at which the system proves to be devoid of the power to generate interposed between said anode and said electron source; an energy extracting coupling associated with said circuit having effectively opposed in phase terminations; and a capacitance including lead from the said control grid to means for selectively making conductive contact with either one of the said energy extracting coupling terminations; whereby making therewith the right termination connection serves to automatically revive the power to generate at the ultra high frequencies desired.

2. The combination of claim 1, in which the length of the control grid lead determines in part the neighborhood of the frequency at which the power to generate ceases.

3. The combination of claim 1, in which a capacitance interposed between the control grid and the electron source determines in part the neighborhood of the frequency at which the power to generate ceases.

4. The combination of claim 1, in which a combination of the length of the control grid lead and a capacitance interposed between the control grid and the electron source determines in part the neighborhood of the frequency at which the power to generate ceases.

5. The combination of claim 1, in which cessation of the power to generate in moving upwards in frequency is overcome by the control grid lead being terminated in the anode side of the paralleled inductance and variable capacitance circuit in lieu of being terminated in one of the terminations of the energy extracting coupling.

6. The combination of claim 1, in which the capacitance in the lead from the control grid comprises a conductive plate positioned abreast of a conductive plate acting as one of the terminations of the energy extracting coupling.

7. In a system for generating electrical alternating currents of sinusoidal wave form in a region of ultra high frequencies somewhere in which the inherent nature of the system per se renders it without the power to further generate: the combination of a standard electronic tube having an electron source in spaced relation to an effective electron attracting positive potential anode and a negative potential control grid interposed therebetween in normal spaced relations thereto; a positive potential screen grid interposed between said grid and anode; a plurality of circuits comprising paralleled inductance and variable capacitance and means for conductively interposing any one of said circuits between said anode and said electron source; an energy extracting coupling associated with a newly chosen one of said circuits having effectively opposed in phase terminations; and a capacitance including lead from said control grid to means for selectively making contact with either one of said terminations of said energy extracting coupling of the newly chosen circuit; whereby generation of electrical alternating currents can be effectively continued at frequencies well beyond the neighborhood of the frequency at which the power to generate ceased due to the replaced circuit no

longer being electrically qualified to support generation.

8. The combination of claim 7, in which all of the energy extracting couplings terminations are so positioned as to be separately and predeterminedly connected to the control grid lead through a single selectively control mechanism.

9. The combination of claim 7, in which all of the energy extracting couplings terminations respectively terminate in conductive plates so positioned as to be separately and predeterminedly capacitive connected to the control grid lead through a single selectively controlled conductive plate.

10. The combination of claim 7, in which cessation of the power to generate in moving upwards in frequency is overcome by the control grid lead being terminated in the anode side of the paralleled inductance and variable capacitance circuit in lieu of terminating the same in one of the terminations of the energy extracting coupling.

11. The combination of claim 7, in which the variable capacitance for the plurality of circuits consists of elements designed with sufficient mass to materially reduce the inherent ohmic resistances and inductive reactances of the same at the ultra high at least frequencies involved.

HOWARD J. TYZZER.
